Primary Examiner — Marie D. Fast Horse(74) *Attorney, Agent, or Firm* — Knobbe, Martens, Olson & Bear, LLP(57) **CLAIM**

The ornamental design for a docking station, as shown and described.

DESCRIPTION

FIG. 1 is a top, front and right side perspective view of a docking station embodying our new design;

FIG. 2 is a bottom, rear and right side perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

In the drawings, the claimed design is defined by the solid lines and shaded surfaces; the dot-dash broken lines immediately adjacent shaded surfaces represent boundary of the claim which extend to the boundary but do not include the
